Patented Aug. 26, 1919.

Nikolaus Gerson, ^{INVENTOR}
BY Diederichs & Fairbank.

ATTORNEYS.

UNITED STATES PATENT OFFICE.

NIKOLAUS GERSON, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

ATTACHMENT FOR WATER OR FLUID HEATERS WITH FAUCETS.

1,314,324.

Specification of Letters Patent. Patented Aug. 26, 1919.

Application filed March 17, 1919. Serial No. 283,096.

To all whom it may concern:

Be it known that I, NIKOLAUS GERSON, a subject of the Government of Austria, having resided in the United States one year last past and having declared my intentions of becoming a citizen thereof, residing in the city and county of Philadelphia, State of Pennsylvania, have invented a new and useful Attachment for Water or Fluid Heaters with Faucets, etc., of which the following is a specification.

My invention consists of a novel device for connecting a water or fluid heater with a faucet or other device adapted to supply said heater with fluid or water, the same consisting of novel means for supporting and retaining the heater on the spout of the supply device, and forming a tight joint with said spout and rendering the parts adjustable to different sizes of supply devices and heaters.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation partly broken away of an electric water heater, and a side elevation of a water-supply attachment therefor embodying my invention.

Fig. 2 represents a vertical section on an enlarged scale of a portion of the attachment on line 2—2 Fig. 1.

Fig. 3 represents a plan view of a detached member of the attachment.

Fig. 4 represents a perspective view of said member.

Similar numerals of reference indicate corresponding parts in the figures.

Referring to the drawings.

1 designates an electric water heater which broadly considered is known in the art. Extending from the casing of said heater is the water receiving chamber 2, the same having its top wall 3 seated against the discharge end of the spout or nozzle 4 of a suitable faucet or other source of supply of water for the heater 1.

Rising from the chamber 2 is the nipple 5 which is in communication with the interior of the latter and is adapted to project

into the terminal of the nozzle 4 as shown in Fig. 2 for a purpose to be hereinafter explained.

In the wall of the casing back of the chamber 2 is the port 6 which forms a communication for said chamber with the interior of the heater 1, whereby the latter may be supplied with water.

The top wall 3 of the chamber 2 forms a ledge on which is placed the gasket or packing 8 with which the edge of the spout 4 contacts, thus making a water tight joint 65 for the faucet with the heater as the water leaves the nozzle 4 and so enters the nipple 5 and is directed by the latter into the chamber 2.

Rising from the sides of the chamber 2 are the ears 9 in the openings 10 of which are connected the lower links of the chains 11, or flexible straps if desired, the upper links whereof are fitted on the corrugated or serpentine arms 12, the outer ends 75 of the latter being formed with the coils 13 which are continuous with the yoke 14, said coils rendering said arms resilient so as to elevate said arms and exert an upward draft on the chains 11, retaining the latter taut, 80 thus holding the ledge or wall 3 of the water chamber, and consequently the gasket thereof water tight against the edge of the spout of the faucet.

The yoke 14 is fitted on the shouldered 85 neck of the casing of the faucet so as to embrace the same, and the bolt 15 is passed through the coils at the side of said casing and tightened by the thumb nut 16, thus clamping the yoke to the faucet and holding 90 the arms 12 flaring therefrom, and with them the chains 11, thus causing an effective connection of the heater with the mouth or edge of the discharge nozzle of the faucet while the corrugations of the arms 12 forming separate shoulders in the length of said arm admit of the adjustment of said chains 11 at different places and tension on the arms 12, while said chambers are held upwardly in properly taut condition.

The chains may be disconnected from the arms 12, and the latter released from the casing of the faucet by removing the nut 16 and bolt 15, the heater thus being disengaged from the faucet as is evident.

Having thus described my invention what

100

105

I claim as new and desire to secure by Letters Patent, is:—

1. An attachment for a fluid heater with a fluid supply device therefor consisting of a resilient arm which is provided with means for connection with said device, and a member which is adapted to extend from said arm to a portion of the body of said heater and engage therewith.
- 10 2. An attachment for a fluid heater with a fluid supply device therefor consisting of a resilient arm which is provided with means for connection with said device, and a member which is engageable with said arm and
- 15 3. A heater for water, a chamber on the casing of the heater for supplying the latter with water, said chamber having an inlet, a flexible device on said chamber adapted to support the chamber, a wall of said chamber at said inlet being adapted to have the outlet end of the nozzle of a faucet or the like seated thereon, an arm attachable to said device, and a yoke adapted to be clamped to the casing of said faucet or the like and carry said arm, said arm being of corrugated form adapted to have said flexible device adjustably connected with the former at different places thereof.
- 20 4. A heater for water, a water receiving chamber therefor, the same having a supply inlet leading from a faucet or the like to the interior thereof, and an outlet forming a communication for the chamber with the interior of the heater, a flexible connection on said chamber and consequently said heater for holding the latter tightly against the mouth of the nozzle of said faucet or the like, a resilient arm attachable to said holder, and means for clamping said arm to the casing of said faucet or the like.
- 25 5. A water heater, a water receiving chamber therefor, the same having a supply inlet leading from a faucet or the like to the interior thereof, and an outlet forming a communication for the chamber with the interior of the heater, a flexible connection on said chamber and consequently said heater for holding the latter tightly against the mouth of the nozzle of said faucet or the like, a resilient arm attachable to said holder, and means for clamping said arm to the casing of said faucet or the like.

NIKOLAUS GERSON.
